DISPOSABLE BLOOD PRESSURE CUFF AND TRANSDUCER

Sydney Hudspith, San Diego, Calif., assignor to Ivac
Corporation, San Diego, Calif.

Filed Nov. 1, 1971, Ser. No. 194,776

Term of patent 14 years

Int. Cl. D24—02

U.S. Cl. D83—12

Fig. 1

Fig. 2

Fig. 3

Fig. 4

FIG. 1 is a front perspective view of a disposable blood pressure cuff and transducer showing my new design and illustrating the flexible nature of the cuff;

FIG. 2 is a rear elevational view of the cuff and transducer shown in FIG. 1, with the cuff in the flat state;

FIG. 3 is a right side elevational view of the cuff and transducer shown in FIG. 2; and

FIG. 4 is a bottom plan view of the cuff and transducer shown in FIG. 2.

I claim:

The ornamental design for a disposable blood pressure cuff and transducer, as shown.
